UNITED STATES PATENT OFFICE.

WILLIAM C. CODMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A TEAPOT OR SIMILAR ARTICLE.

46,162.

Specification for Design.

Patented July 28, 1914.

Application filed March 11, 1914. Serial No. 824,065. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for Teapots or Similar Articles, of which the following is a specification, reference being had to the accompanying drawing.

I claim—

The ornamental design for a tea pot or similar article, as shown.

WILLIAM C. CODMAN.

Witnesses:

ADA E. HAGERTY,
J. A. MILLER.
